UNITED STATES PATENT OFFICE.

WILLIAM F. SMITH, OF BROOKLYN, NEW YORK, ASSIGNOR TO WESTERN ELECTRIC COMPANY, OF NEW YORK, N. Y., A CORPORATION OF ILLINOIS.

FIRE AND POLICE ALARM BOX.

1,147,052.

Specification of Letters Patent. Patented July 20, 1915.

Application filed August 7, 1912. Serial No. 713,740.

To all whom it may concern:

Be it known that I, WILLIAM F. SMITH, a citizen of the United States, residing at Brooklyn, in the county of Kings and State 5 of New York, have invented a certain new and useful Improvement in Fire and Police Alarm Boxes, of which the following is a full, clear, concise, and exact description.

This invention relates to signal transmitting devices, and is particularly adaptable for use in connection with police and fire alarm telegraph and telephone systems although its use is not limited exclusively to this field of operation.

15 The general object of this invention is to provide a new and improved form of signal transmitting device which will transmit a plurality of signals, and which is simple in construction and efficient in operation.

20 To the above end, this invention comprises, in its preferred form hereinafter described, a spring-driven train which drives a multiple signal transmitter, and means such as a plurality of key mechanisms, for 25 operating the spring-driven train and for controlling the signal impulses which the transmitter is adapted to produce.

This invention will be fully understood from the following description taken in connection with the accompanying drawings 30 in which the invention is shown as embodied in a police telegraph and telephone box.

In the drawings—Figure 1 is a perspective view of a signal transmitting device 35 having my invention embodied therein, the inside door of the box in which the mechanism is mounted and the controlling keys being shown in dotted lines; Fig. 2 is a top plan view of the mechanism shown in Fig. 1; Fig. 3 is a front elevation thereof; Figs. 4 and 5 are front elevations of certain parts of the mechanism; Fig. 6 is a perspective view of the police box showing the door thereof in its open position; and Fig. 7 40 shows in perspective the end of the key used with the signal transmitter in which this invention is embodied.

A spring-driven train and the signal transmitting and controlling mechanisms 50 are secured within the housing 1 against the front wall thereof by means of supporting legs 5 and 6. Two plates 7 and 8, drilled to furnish bearings for the various shafts are held the proper distance apart by columns 9 and 10, and are rigidly secured to

the supporting legs 5 and 6. The shaft 11 serves as the main driving shaft and carries at one end a helical spring 12 secured at one end to the shaft and at the other end to a fixed pin 13. A driving wheel 14 riding 60 loosely on the shaft 11 is provided with a spring pressed pawl 15 adapted to engage the teeth of a ratchet wheel 16 rigidly secured to the shaft 11. When the shaft 11 is revolved to wind the spring 12, the pawl 15 65 rides over the teeth of the ratchet wheel 16, allowing the driving wheel 14 to remain at rest. Upon the release of the shaft to allow the spring to unwind, the pawl 15 locks with one of the teeth of the ratchet wheel 16 70 causing the driving wheel 14 to turn with the shaft. A spring member 17 secured to the driving wheel 14 bears against the plate 8 and serves to keep said driving wheel in such a position on the shaft that the pawl 75 15 carried thereby may be placed in operative position to the ratchet wheel 16.

The main driving wheel 14 meshes with a pinion 18 rigidly secured to a shaft 19 imparting motion thereto. The shaft 19 carries in addition to the pinion 18 a gear wheel 20 and two toothed contact wheels 21 and 22. The gear wheel 20 meshes with a pinion 23 on a shaft 24 which also carries an escapement wheel 25. An escapement pawl 80 26 is provided to engage the teeth of the escapement wheel 25 and serves to regulate the speed of rotation of the spring motor train. A stop lever 27 rigidly secured to the shaft 11 is adapted to contact with a forward stop pin 28 and a back stop pin 29 85 which are so spaced that as the shaft 11 rotates from the forward to the back stop the shaft 19 makes one complete revolution. The driving shaft 11 also carries a rigidly attached collar 35 which is milled at its outer end to be engaged by the wards of the proper key inserted in the keyhole 36 over the projecting pin 37. The key may be similar to the one shown in Fig. 7 except that the long ward 53 may be omitted.

A crank lever 38 riding loosely upon the shaft 11 is secured to the loose crank lever 39 by means of the collar 40 and is adapted 105 to impart motion thereto, and to actuate and be actuated by the shaft 11 in the following manner: The rigid bearing shaft 41 is provided with a rotatable collar 42, having a milled projection adapted to engage 110

the ward of a key inserted in key hole 43, and a crank lever 44 secured thereto. A link member 45 is pivotally connected to the cranks 38 and 44 by pins 46 and 47, and serves to connect them together. A pin 48 carried by the crank 38 projects into a slot 49 in the collar 35 and is normally in a position to contact with the forward end thereof in case the crank 38 is rotated. It will thus be readily apparent that if the collar 42 is rotated, motion is imparted to the shaft 11 through the agency of the cranks 38 and 44, the link 45 and the pin 48. The crank lever 39 is also caused to rotate through the agency of the connecting collar 40. On the return motion of the shaft 11 caused by the unwinding of the spring, the cranks 38, 39 rotate with the shaft 11, and the crank 44 rotates about the rigid shaft 41 since the forward edge of the slot 49 bears against the pin 48. On the other hand, when the spring is wound by a key operating on the collar 35, the forward or return movement thereof will not actuate the cranks 38, 39 and 44 since the pin 48 rides idly in the slot 49.

A spring-pressed pawl 50 pivotally secured to the supporting leg by means of a pin 51 is adapted to normally engage a milled lug 52 on the collar 42 preventing its rotation. This construction makes it necessary to insert a key with a long ward similar to 53, Fig. 7, adapted to disconnect the pawl 50, into the hole of the collar 42 before the spring train can be wound.

The circuit-closing mechanism consists of the contact wheels 21 and 22 and contact brushes 55 and 56 adapted to be engaged by the teeth thereof. The contact wheel 21 is provided with a single long tooth 57 and the contact wheel 22 is provided with teeth 58 arranged to transmit a code signal. In the mechanism shown in the figures, three sets of four teeth are provided, but this may be varied to suit the conditions. The contact brushes 55 and 56 are connected together and supported by, but insulated from, the frame by screws 59 and constitute one side of a break in the signaling circuit. The contact wheels 21 and 22 constitute the other side of the break, and it will be readily understood that whenever one of the teeth of the wheels 21 and 22 contact with one of the brushes 55 and 56 the circuit will be complete. If a suitable source of energy is inserted into the circuit an impulse will be imparted into the line when the circuit is thus closed.

The contact brush 55 is normally held in a position to be engaged by the teeth of the contact wheel 22, and when the mechanism is wound and released a code signal, in the illustrated transmitter 4-4-4, is always produced. The contact brush 56 is in alignment with, but is normally held out of en-

gagement with the tooth 57 of the contact wheel 21 by means of a laterally projecting lug 65 of a link member 66. Thus unless released as hereinafter described, the long impulse due to the tooth 57 contacting with brush 56 is not imparted to the line.

The link member 66 is pivotally supported at one end by a pin 67 and carries at its free end a roller 68 adapted to rotate about the pin 69. The roller 68 normally rests in a saddle 70 of the crank 39 and is subjected to downward pressure by a spring 71. The spring 71 is secured at one end to the frame by screws 59, the free end resting on a laterally projecting lug 72 of the link 66. When the crank 39 is in its normal or vertical position the roller 68 rests in the saddle and holds the link 66 in such a position that the brush 56 is out of engaging position with the tooth 57 of the contact wheel 21. If, however, the crank 39 is rotated about the shaft 11 as hereinbefore described, the saddle support is removed from beneath the roller 68 and the downward pressure of the spring 71 causes the link 66 to be lowered until the brush 56 is in operative relation to the tooth 57. Upon the return movement of the spring-driven train, both brushes 55 and 56 contact with the teeth of their respective contact wheels 21 and 22. The crank 39 in returning to its normal position raises the link 66 so that the brush 56 after contacting with the tooth 57 is removed from operative relation therewith until again released as hereinbefore described.

In service a code signal is transmitted by inserting the proper key in the key-hole 36 and turning it to the right until the stop lever 27 strikes the forward pin 28. The spring train is thus placed in operative condition by the winding of the spring 12. The key should then be released to allow the spring train to unwind, causing the contact wheels 21 and 22 to make one complete revolution. The brush 55 being in operative relation with the contact wheel 22, and the brush 56 being held out of engaging position with the contact wheel 21, the signal 4-4-4 is transmitted.

If it is desired to transmit a different signal, as, for example, an emergency signal, a key with a long ward is inserted in the key-hole 43 and given a turn to the right as before. The spring is again wound and the brush 56 is lowered to a position to be struck by the tooth 57. The key should then be released to allow the spring train to unwind as before and since both brushes 55 and 56 are in operative relation to the teeth of their respective wheels, the signal 4-4-4 is transmitted preceded by an impulse of longer duration.

I claim—

A current impulse transmitter comprising a spring-driven escapement-regulated mech-

anism, two toothed contact wheels driven thereby, a contact brush mounted in operative relation to one of said wheels, a second contact brush in alinement with but normally held out of operative relation to the second wheel, a key-operated shaft for causing the operation of said contact wheels, a second key operated shaft, a system of cranks and levers connected thereto and to 10 said first-mentioned shaft for causing the operation of said contact wheels and allow-

ing the second brush to move into operative relation to its contact wheel, and a spring-pressed pawl for normally locking said second-mentioned shaft.

In witness whereof, I hereunto subscribe my name this 1st day of August A. D., 1912.

15 WILLIAM F. SMITH.
